Patented Jan. 10, 1922.

FIG. 1.

FIG. 2.

FIG. 6.

FIG. 3.

FIG. 4.

FIG. 5.

M. H. Ballou, INVENTOR
Victor J. Evans
BY ATTORNEY

UNITED STATES PATENT OFFICE.

MARCUS H. BALLOU, OF PITTSBURGH, PENNSYLVANIA.

TAPE ATTACHMENT.

1,403,376.

Specification of Letters Patent. Patented Jan. 10, 1922.

Application filed July 15, 1921. Serial No. 485,025.

To all whom it may concern:

Be it known that I, MARCUS H. BALLOU, a citizen of the United States, residing at Pittsburgh, in the county of Allegheny and State of Pennsylvania, have invented new and useful Improvements in Tape Attachments, of which the following is a specification.

This invention relates to an attachment for a tape line for convenience in taking measurements from a fixed object.

This invention is intended more particularly as an improvement over the device disclosed in my Reissue Patent #14947 of September 10, 1920, one of the main objects being to provide means whereby the attachment may be readily folded so as to occupy a minimum of space when placed in the pocket. A further object is to provide a device which, when folded, will be free of all unnecessary projections so as to permit the same to be readily inserted into or removed from the pocket. Another object is to provide a device which may be readily produced at small cost by stamping and bending from sheet metal. Further objects will appear from the detailed description.

In the drawings:—

Figure 1 is a top plan view of the device in folded condition;

Figure 2 is a side view of the device as applied;

Figure 3 is a top plan view of the device as applied;

Figure 4 is a fragmentary top plan view of the body plate;

Figure 5 is a detail of the head plate;

Figure 6 is a section taken substantially on line 6—6 of Figure 1.

The device includes a body plate 1 of substantially rectangular shape which may be readily stamped from sheet metal and is provided at one end with a point 2. This body plate is formed with integral tabs 45 which are turned over at right angles to provide arms 3 and 4 remote from the ends of the plate, and arms 5 and 6 at the free end of the plate, these latter arms having their adjacent ends spaced apart to provide 50 a slot 7 for insertion of a tape *a*. The arms 3 and 4, as well as arms 5 and 6, are oppositely directed and are spaced from the upper face of plate 1 for reception of the tape line, these arms serving to hold the tape 55 in proper alignment with the plate and to prevent casual displacement of the tape.

Plate 1 is further provided, adjacent to point 2, with two openings 8 and with two tabs 9 positioned adjacent to the inner end of point 2, each of these tabs being formed 60 with an outwardly projecting finger 10.

A head plate 11 is stamped from sheet metal and is provided with a cross bar 12 from which extend arms 13. Two tabs 14 project from the cross bar equidistant from 65 a post 15 which is adapted to receive a terminal loop *b* secured to one end of tape *a*. Tabs 14 are inserted through openings 8 of plate 1 and are bent to form sleeves, the tabs 9 being turned over or bent to provide 70 sleeves which are in alignment with the sleeves formed from tabs 14. A pintle pin 16 is inserted through the aligned sleeves and serves to hingedly secure the head plate to the body. In bending tabs 9 fingers 10 75 thereof are so positioned as to contact with head plate 11 when the same is turned in one direction into position at right angles to the body plate 1, as in Figure 2. To accommodate post 15 point 2 of plate 1 is further 80 provided with a central opening 17, and head plate 11 is provided with an opening 18 corresponding to point 2 so that the head plate may be turned into parallelism with body 1, the bar 12 serving as a stop element 85 to limit turning movement of the head plate in the other direction.

By turning the head plate 11 into vertical position at right angles to body plate 1, the device may be readily applied to a rail *C*, 90 as illustrated in Figure 2, or any other fixed object from which it is desired to take a measurement. The point 2 may be used for securing the device to an object formed of wood or other material into which the 95 point can be driven.

What I claim is:—

1. In a device of the character described, a body plate, a head plate hinged to said body plate so as to be moved into parallelism therewith or at right angles to the body plate, optionally, means for limiting turning movement of the head plate in one direction, means for limiting turning movement of the head plate in the other direction, and means for attaching a tape to the head plate. 100

2. In a device of the character described, a body plate, a head plate connected to said body plate and movable into parallelism therewith or at right angles to the body plate, optionally, and means for limiting movement of the head plate when turned 110

into position at right angles to the body plate, said head plate being provided with an element adapted for reception of a member secured to a tape.

3. In a device of the character described, a body plate, a head plate, aligned sleeves carried by the head plate and the body plate, a pintle passing through said sleeves for hingedly connecting said plates, and stop elements carried by the body plate positioned to limit movement of the head plate in one direction beyond a position at right angles to the body plate, the head plate being adapted for reception of a terminal loop secured to a tape.

4. In a device of the character described, a body plate provided at one end with aligned sleeves and with spaced openings, a head plate provided with sleeves projecting through the openings of the body plate and disposed in alignment with the sleeves of said body plate, a pintle secured through said sleeves, means for limiting turning movement of the head plate in one direction beyond a position at right angles to the body plate, and means for attaching a tape to said head plate.

5. In a device of the character described, a body plate provided at one end with aligned sleeves and with spaced openings, a head plate provided with depending arms and with a cross bar connecting the same, the head plate being further provided with

sleeves projecting through said openings and disposed in alignment with the sleeves of the body plate, a pintle secured through said sleeves, a post secured to the cross bar and disposed in the plane of the head plate, the body plate being provided with an opening to accommodate said post, and means for limiting turning movement of the head plate beyond a position at right angles to the body plate.

6. In a device of the character described, a body plate provided at one end with a point and with aligned sleeves and spaced openings adjacent to said point, a head plate provided with an opening to accommodate the point of the body plate, the head plate being provided with arms extending from said opening and with a cross bar connecting said arms, said head plate being further provided with a post element projecting from the bar and with spaced sleeves attached to the bar and extending through the openings of the body plate in alignment with the sleeves of said body plate, the point of the body plate being provided with an opening to accommodate said post, a pintle secured through said sleeves, and means for limiting turning movement of the head plate in one direction beyond a position at right angles to the body plate.

In testimony whereof I affix my signature.

MARCUS H. BALLOU.
